UPHOLSTERY FABRIC

Ann Franke Gonzalez, New York, N. Y., assignor to Collins & Aikman Corporation, New York, N. Y., a corporation of Delaware

Application December 28, 1955, Serial No. 39,512

Term of patent 3½ years

(Cl. D92—1)

The figure is a plan view of an upholstery fabric showing my new design. A unit of the design is indicated in broken lines in the drawing. Such unit is repeated in regular succession throughout the fabric.

I claim:

The ornamental design for an upholstery fabric, as shown and described.
